SLUG FOR CLEANING CASTINGS.

Application filed March 3, 1926. Serial No. 92,018.

This invention relates to improvements in slugs for use in tumbling-barrels and is intended especially for use in foundries.

The particular object of this invention is, to provide slugs which have not only a peculiarly efficient shape for their cleaning action upon the castings with which they are tumbled, but, in addition thereto, to provide slugs to be made of a material selective as to its degree of hardness, ranging from that of soft wrought iron, to that of high-carbon steel.

My improved slugs are fully described in the following specification, which, taken together with the accompanying drawings, is sufficiently full, clear and exact to enable others skilled in the arts to which its construction and use respectively relate, to make and use the same.

20 In the manufacture of my improved slugs, they are sheared, or otherwise severed, from rolled bars or rods having an angular cross section, and which have been twisted after rolling.

25 One well-known form of such bar is shown upon page 124, of the 19th edition, date January 1, 1917, of the Pocket Companion, published by Carnegie Steel Company, Pittsburgh, Pennsylvania.

30 It is shown in said publication that "cold twisted square bars," ranging in sizes from one-quarter of an inch square, up to two inches square, are a commercial product.

Referring now to the drawings:

35 Fig. 1 is an end view of a square twisted bar, which is the preferred form of bar used in making my improved slugs.

Fig. 2 is a side elevation of the bar shown in Fig. 1.

40 Fig. 3 is an end view of a slug formed from a square, twisted steel bar, like that shown in Figs. 1 and 2.

Fig. 4 is a side view of the slug shown in Fig. 3.

45 Fig. 5 is an end view of a triangular, twisted bar,

Fig. 6 is an end view of a twisted bar having an oblong, rectangular cross section,

50 Fig. 7 is an end view of a twisted bar having a hexagonal cross section, all of which sections are suitable for the manufacture of my improved slugs.

Fig. 8 is a view intended to illustrate the point that, in shearing my improved slugs from the bar, said bar is, preferably, posi-

tioned with its longitudinal axis at an angle to the cutting edge of the shear-blade.

Referring especially to said Fig. 8, it is explained that the reason for said angular disposition of the bar 1 to the cutting edge 2 of the shear-blade is, to cause the severed faces 3, 4, of the slugs to be angularly disposed, both to the longitudinal axis of the slug and to the helical, sinuous angles, and to the lateral, circumferential faces thereof, such as the angles or corners 5 and the faces 6, since it is the multiplicity of variously and differently-disposed angles, corners and faces, together with the sinuous, helical, characteristics thereof which impart to my improved slugs their peculiarly efficient impinging, glancing, sand-removing, cleaning and smoothing action upon the castings with which they are tumbled.

55 In the process of shearing my improved slugs from the twisted bar, when the bar is disposed at said angle to the cutting edge of the shear-blade, each time said bar 1 is fed forward for a new cut, it is, preferably, turned in co-ordination or harmony with the lead of the screw-like or twisted characteristic of the bar, as though said bar were passing through a fixed nut formed to co-operate therewith; this revolving movement causes the sheared or severed faces of the slug to be differently disposed,—rotatively considered—so that said faces are disposed at an angle to each other, instead of being parallel, as they would be, were the bar not rotated at each forward feed movement thereof.

60 I have found, in the actual use of my improved slugs, that the most efficient length of same, is equal to one and one-quarter times the diameter of the slug, or the bar from which it is severed.

65 It is now a fairly uniform practice with the mills which manufacture twisted bars of angular cross section, to make the lead of the twist equal to either ten or twelve diameters of the bar. This statement is made for the purpose of indicating in a general way, the degree of angularity of the sheared faces of the slug and the relative position of their respective planes, rotatively of the slug. However, since a fairly efficient slug may be made without imparting a rotative movement to the bar in feeding same to the shear, I do not wish to be understood as confining myself to a slug that is made by the

employment of such rotative movement only.

In Figs. 1, 5, 6 and 7, the shaded areas are employed to more prominently indicate the various cross sections of forms of twisted bars that I consider well adapted for use in the manufacture of my improved slugs. It will be noted that all of these forms have angular cross sections, as distinguished from round, oval or other non-angular forms.

10 By an inspection of the drawings it will be readily noted that all the shapes shown therein are polygons, that is to say, the faces of said shapes are straight, flat faces, and the meeting points of said faces are angles.

15 I claim the following:

1. Slugs for use in cleaning castings consisting of pieces severed from twisted metallic bars having an angular cross-section, the severed faces of said slugs being

20 disposed at an angle other than 90° to the longitudinal axis of the slug.

2. Slugs for use in cleaning castings con-

sisting of pieces severed from a twisted bar having an angular cross-section, the severed faces of said slugs being disposed at an angle 25 to each other and at an angle other than 90° to the longitudinal axis of the slug.

3. Slugs for use in cleaning castings consisting of oblong metallic pieces of a cross section having the shape of a regular polygon and winding, helically-disposed lateral, circumferential faces, and their end faces disposed at an angle to each other and at an angle other than 90° to the longitudinal axis 30 of the slug.

35 4. Slugs for use in cleaning castings consisting of pieces sheared from a bar of metal having the cross-sectional shape of a regular polygon, the sheared faces being disposed at an angle of other than 90° to the 40 axis of the bar.

In testimony whereof I affix my signature.
